UNITED STATES PATENT OFFICE.

ROBERT J. MONTGOMERY, OF CHICAGO, ILLINOIS.

FLUE-CLEANER.

1,266,140.

Specification of Letters Patent.

Patented May 14, 1918.

Application filed February 23, 1915. Serial No. 10,063.

To all whom it may concern:

Be it known that I, ROBERT J. MONTGOMERY, a citizen of the United States, residing at Chicago, in the county of Cook, 5 State of Illinois, have invented certain new and useful Improvements in Flue-Cleaners, of which, the following is a specification, reference being had to the accompanying drawings.

10 This invention relates to flue cleaners and is especially designed for use for cleaning the flues of a tubular boiler, although it can be used for cleaning tubes under any other circumstances, as desired. The invention 15 relates particularly to that type of flue cleaners involving the use of a rotary cutting device which is adapted to be projected into or through a flue by the use of steam, yielding means being provided for returning the cleaning tool after it has been projected through the flue. It is one of the 20 principal objects of my invention to provide means in a device of this type for protecting from the moisture and the pressure of the 25 steam the housing and the apparatus located therein by which the flexible means for returning the cutting tool is actuated.

It is another object of my invention to 30 provide a stop device which may be automatically brought into action for stopping the movement of the reel and the forward movement of the cable when the cutting device reaches the end of its forward movement, such automatic stop being adapted to 35 operate without strain upon the reel, yielding cushioning means being preferably interposed. It is another object of my invention to provide an improved form of indicating device by which the operator is enabled to determine readily the position of 40 the cutting tool in the tube being cleaned. It is another object of my invention to provide improved yielding means against which the cutting tool is brought to rest 45 upon its return to normal position after a cleaning operation.

It is another object of my invention to 50 provide an improved form of cutting tool for use with devices of this type. It is another object of my invention to provide a new and improved form and arrangement of parts by which the device as a whole shall be very strong and compact. It is another object of my invention to improve the

means for adjustably supporting the flue 55 cleaner. It is another object of my invention to improve flue cleaners in sundry details hereinafter pointed out.

The preferred means by which I have accomplished my objects are illustrated in the 60 accompanying drawings and are hereinafter specifically described. That which I believe to be new and desire to cover by this application is set forth in the accompanying claims.

In the drawings:

Figure 1 is a side view of my improved device, showing a fragmentary portion of the tube of a tubular boiler, and showing in cross-section the trolley-track by which the 70 device is supported;

Fig. 2 is a central vertical section through the housing which contains the mechanism at the rear of the device, being substantially a section taken on line 2-2 of Fig. 7;

Fig. 3 is a view, partly in section, showing the inside face of one of the side walls of the housing, together with the mechanism mounted thereon, being taken substantially on line 3-3 of Fig. 2;

Fig. 4 is a longitudinal central vertical section through the rear part of the device, being taken substantially on line 4-4 of Fig. 2, but showing the parts in changed position with the cable extended at full 85 length;

Fig. 5 is an enlarged detail, being a view taken substantially at line 5-5 in Fig. 2;

Fig. 6 is a detailed view, showing the mounting of the spring buffer device which 90 serves as a stop at the end of the forward movement of the cutting device, being a section taken substantially on line 6-6 of Fig. 4;

Fig. 7 is a view of the housing with one 95 of the side walls thereof removed, being taken substantially on line 7-7 of Fig. 2;

Fig. 8 is an enlarged detail, being a longitudinal central sectional view of the forward end of the device, with the cutting 100 tool projected out of normal position relative thereto;

Fig. 9 is an enlarged detail showing the means for centering the cable-inclosing pipe in the steam-pipe, being substantially a section taken on line 9-9 of Fig. 8;

Fig. 10 is an enlarged detail, being a perspective view of the bracket forming the

means of connection between the housing and the steam-pipe.

Fig. 11 is an enlarged detail showing a fragmentary portion of the body-portion 5 of the housing;

Fig. 12 is a view of the cutting tool as seen from in front, the view being taken substantially on line 12—12 of Fig. 1;

Fig. 13 is an edge view of the cutting device shown in Fig. 12;

Fig. 14 is an enlarged detail showing a fragmentary view of a boiler tube with the cutter in operative position therein; and

Fig. 15 is a top view of the bracket-member 15 by which one end of the supporting chain is adjustably held.

Referring to the several figures of the drawings in which corresponding parts are indicated by the same reference characters,— 20 indicates a housing (see Fig. 1), extending forward from which is a steam pipe 21 provided at its front end with a tapering engaging member 22 adapted to be inserted in the end of a flue 23. As best shown in Figs. 4 and 8, the steam pipe 21 has extending through it a smaller pipe 24 through which a cable 25 is adapted to run, the pipe 24 serving to protect the cable 25 30 from the steam as hereinafter described. The cable 25 has revolvably connected to its forward end means adapted to be rotated by steam passing forward through the pipe 21, such means comprising a cutting device 35 26 to be hereinafter described. The rear end of the cable 25 is adapted to be wound upon a reel 27 revolvably mounted in the housing 20, such reel being rotated for permitting the forward movement of the cutting device 26 against the action of a spring 40 28 which serves at the end of the forward movement of the cutting device to rewind the cable upon the reel for retracting the rotary cutting device. An indicating device 45 29 is provided for indicating the position of the cutting device relative to the end of the steam pipe 21, and a steam valve 30 is provided for shutting off the steam as desired when the rotary cutting device 50 reaches the end of its stroke as shown by the indicating device 29. The device as a whole is adapted to be supported by a flexible chain or cable 31 secured to the device as a whole at two points and running over 55 a pulley 32 suspended from a trolley 33 operating upon a track 34 extending transversely of the boiler at the end thereof at which access is had for cleaning the flues.

The housing 20 comprises a drum-like 60 portion 35 closed at one side by a head 36 formed integral therewith and closed at its other side by a head 37 adapted to be secured in position thereon by means of screws or in any other suitable manner.

65 The housing also comprises a bracket 38

having formed integrally therewith a tubular portion 39 for the connection of the steam pipe thereto. As is best shown in Figs. 7 and 10, the bracket 38 comprises also a triangular corner plate 38^a by which the construction is materially reinforced. As is best shown in Figs. 10 and 11, the drum-member 35, the side-closure plate 36 and the bracket 38 are so formed as to fit snugly together for forming a tight housing. As is best shown in Fig. 4, the rear end of the pipe 24 is inserted in the forward end of the tubular portion 39, being held therein by means of screw-threads, forming thus a tight joint between them. 75 A Y-connection 40 is connected by means of screw-threads upon the forward end of the tubular portion 39, in the forward end of which connection the rear end of the steam pipe 21 is secured by means of screw-threads. A steam pipe 41 is also connected by means of screw-threads to the Y-connection 40, leading therefrom in a diagonal direction and being secured by clamping blocks 42—43 to the drum-portion 35 of the 80 housing. The steam valve 30 is connected to the lower end of the steam pipe 41, a pipe 44 being provided for connecting the valve 30 with any suitable source of live steam. By reason of the triangular construction 85 afforded by the diagonally-disposed pipe 41, the vertically-disposed front portion of the drum 35, and the horizontally-disposed tubular portion 39, the parts are very strongly reinforced so as to be insured against 90 breakage under any normal conditions of use.

The means for supporting the device and for handling it in use comprise a handle 45 of wood or other suitable poor conductor of 105 heat secured between two brackets 46—47 which are preferably secured by means of screws to the rear portion of the drum 35. Another similar handle 48 is secured upon the steam pipe 21 by means of brackets 49—50 110 comprising split-sleeves at their lower ends adapted to be tightened upon said pipe. The forward end of the flexible connection 31, which in the construction shown is in the form of a chain, is connected to the pipe 21 by 115 means of a split-sleeve 51 adapted to be tightened about the pipe. The rear end of the chain 31 is adjustably secured by means of a block 52 secured upon the drum 35. As best shown in Fig. 15, the block 52 revolvably 120 supports a roller 53 under which the chain 31 is adapted to run, from which roller the chain extends rearwardly into position between two lugs 54—55. As will be readily understood, the lugs 54—55 serve to hold the 125 chain against longitudinal movement under the roller 53. At the same time the rear end of the chain may be readily lifted out of position between the said lugs, whereupon the chain can be adjusted as desired to vary 130

the length of the supporting portion thereof as desired, whereupon the chain can again be quickly and easily brought into operative engagement with said lugs. In the construction shown the handle 45 is made hollow whereby the rear end of the chain is adapted to extend through the handle so as to be kept out of the way.

As is best shown in Figs. 8 and 9, the forward end of the pipe 24 is centered in the steam pipe 21 by means of screws 56 extending radially through the pipe 21 into contact with the pipe 24. As is best shown in Fig. 8, the tapering engaging member 22 is secured upon the forward end of the steam pipe 21 by means of screw threads whereby it is adjustable slightly longitudinally of the pipe. A conical spring 57 is secured by means of screws 58 within the engaging member 22 and extending forward from the front end of the steam pipe 21, as is best shown in said Fig. 8.

The rotary cutting device 26 is secured to the forward end of the cable 25 in the construction shown through the medium of a rod 59 to which the forward end of the cable is affixed in any suitable manner (see Fig. 14). The rod 59 is provided with a head 60 which is adapted to be brought into contact with the forward end of the conical spring 57 for cushioning the rearward movement of the cutter 26 and the cable 25, thus cushioning also the corresponding movement of the reel 27. As is clearly shown in said Fig. 14, the rotary cutting device is revolvably mounted upon the forward end of the rod 59, being secured thereon by means of nuts 61, or in any other suitable manner.

As is shown clearly in Figs. 12 and 13, the rotary cutter 26 comprises a hub portion 62 by which it is revolvably mounted upon the rod 59. Fixedly secured upon the hub 62 is a plate 63 cut and twisted into the form of a fan or propeller. Upon each of the blades 64 thus formed by the plate 63, upon the rear edge thereof in the direction of rotation of the cutter, there is fixed a cutting device 65, one edge of which is turned to extend forward, thus providing a plurality of cutting edges adapted to engage the soot or other matter deposited upon the inner surface of the flue, as is shown in Fig. 14. As is clearly shown in Figs. 12 and 13, the front edge of each of the blades 64 overlaps the rear edge of the adjacent cutting device 65, by reason of which the steam projected against the rotary cutter is rendered more effective for producing rotation of the said rotary cutter.

As is best shown in Fig. 2, the reel 27 is mounted in the housing 26 by means of a shaft 66 which is suitably journaled in the side walls 36 and 37, the reel 27 being revolvably mounted upon said shaft by means of a hub 67 formed integrally therewith. As is clearly shown in said Fig. 2 the inner end

of the spring 28 is fixedly attached to the shaft 66, the outer end of said spring being secured in any suitable manner to the inner periphery of the drum-portion of the reel 27, as is shown in Fig. 4. Upon the outer end of the shaft 66 adjacent to the side member 36 is fixed a ratchet wheel 68 which is held against rotation relative to the shaft, in the construction shown said ratchet wheel having an angular bearing upon said shaft. A dog 69 is pivotally mounted upon the plate 36 adjacent to the ratchet wheel 68 and adapted to be turned into operative engagement therewith, as is shown in Fig. 5. With the dog 69 in engagement with the ratchet wheel 68 so as to hold the shaft 66 against rotation in clockwise direction in Fig. 5, whereby the said shaft is held against rotation in counterclockwise direction in Fig. 4, the spring 28 serves to resist rotation of the reel 27 in counterclockwise direction in Fig. 4. The shaft 66 is shown in Figs. 1 and 2 projecting beyond the plate 37 of the housing, being square in cross-section for the engagement of a suitable turning tool by which the shaft 66 is adapted to be rotated relative to the reel 27 for tightening or loosening the tension of the spring 28 as desired.

The cable 25 is designed to be of such a length as to correspond to the length of flues which are to be cleaned, the entire length of cable being designed to be run out from the reel upon each actuation of the cleaning device 26. The means for attaching the rear end of the cable 25 to the reel and for yieldingly stopping the forward movement of the cable and the rotary movement of the reel at the end of the forward movement of the rotary cutting device comprises an arm 70 pivotally mounted upon the reel 27 and adapted to move between its extended position as shown in Fig. 4 and its retracted position as shown in Fig. 7. As is clearly shown in Fig. 4, the connection of the rear end of the cable 25 to the arm 70 is such that when the cable extends forward directly from the arm in its extended position as shown in Fig. 4, the free portion of the cable is directly in alignment with that portion of the cable embraced by the arm 70, whereby the likelihood of undue wear upon the cable at the point of its connection to the arm is reduced to a minimum. In the construction shown the arm 70 is mounted in a slot through the drum-portion of the reel 27, being pivotally mounted by means of a pin 71 supported by the web of the reel 27 and by a suitable bracket 72 mounted upon said web. As will be readily understood from an inspection of Fig. 4, when the reel 27 is rotated in clockwise direction from the position shown in said figure the arm 70 is adapted to move inward so as to be almost wholly retracted from its extended position, the upper edge of the arm 70

4
being curved to conform approximately to the curvature of the drum-portion of the reel 27.

As will be readily understood, when the reel 27 is rotating in counterclockwise direction in Fig. 4 in the process of unwinding the final coil of cable 25 from the reel, as the reel 27 approaches the position shown in Fig. 4 the arm 70 will be extended by the 10 pull of the cable thereon into the position shown in said figure. Shortly before the arm 70 reaches the position shown in said Fig. 4 the said arm is brought into contact with the head of a buffer 73 which is mounted in a recess 74 at one side of the tubular portion 39 of the bracket 38, a spring 75 being mounted in said recess to yieldingly resist the forward movement of the buffer 73. The buffer 73 is held against turning 15 in the recess 74 and against withdrawal therefrom by means of a key 76 suitably secured upon the bracket 38 with its inner end engaging a suitable groove 77 in the said buffer.

The indicator 29 is mounted upon the outer end of a pin 78 journaled in the plate 37 having mounted upon its inner end a gear 79, meshing with which is a pinion gear 80 which is mounted upon a pin 81 journaled at one end in the plate 37 and at the other end in a suitable bracket 82 secured to said plate 37. Fixed upon the pin 81 is another gear 83 which meshes with a gear 84 fixed upon the hub 67 of the reel 27. The 20 indicating device 29 is thus geared down relative to the reel 27 whereby in the construction shown the said device 29 is adapted to be given one complete rotation for each rotation of the reel 27 for unwinding such a length of cable as to enable the cutting device 26 to clean a twenty-four foot flue. A graduated plate 85 is fixed upon the plate 37, in the construction shown, adapted to coöperate with the arrow upon 25 the indicator 29 for showing the extent by which the cutting device 26 has been projected forward.

In the operation of the device, when the cutting device 26 approaches the end of its operative stroke as is indicated to the attendant by the position of the indicator 29, the attendant through the use of a braking device can slow down the rotation of the reel so as to be able to close the valve 30 at the proper interval. This braking device 35 comprises a lever 86 pivotally mounted upon the inner face of the plate 37, the turned end 87 of which lever is adapted to be brought into engagement with the inner periphery of the drum-portion of the reel 27. The lever 86 is normally held out of operative position by a spring 88 attached to the lever 86 and to the plate 37. A stop 89 is mounted upon the plate 37 adjacent to 40 the lever 86 adapted to hold the lever 86

against the action of the spring 88 in approximately an operative position.

By the use of my improved construction involving the pipe 24 surrounding the cable 25 at the point where the steam enters the rear end of the steam pipe 21, the steam is prevented from entering the housing 26, the resistance which the steam encounters in its forward movement by reason of being brought into contact with the rotary cutter 26 being insufficient to cause a reversal of direction of the flow of the steam such as would be necessary to cause the steam to flow rearwardly through the pipe 24.

While I have shown the pipe 24 as extending the full length of the pipe 21, I do not wish to restrict myself to that particular construction except as hereinafter specifically claimed, inasmuch as it is believed that a length of pipe 24 about the cable at the rear end of the device such as to direct the steam forward along the pipe 21 would under certain conditions of use be sufficient for preventing the flow of the steam backward within the pipe 24 without extending such pipe 24 to the forward end of the pipe 21. Moreover, I do not wish to restrict myself at all to having the flexible connector 25 extend through the steam-pipe except as hereinafter specifically claimed, the essential feature being that the flexible connector be brought to proper position relative to the cleaning device 26 which is in position to be engaged to advantage by the steam, the arrangement being such that the steam has an unrestricted flow past the point where the flexible connector and the steam are brought to move along parallel or coincident paths whereby the steam is caused to continue its forward flow without danger of changing direction to flow backward along the advancing cable.

While I have described my improved device in both the specification and claims as being operable by steam and as being operated by a supply of steam from any suitable source, and desire to have the device operated by steam for the use with which it is primarily designed, it will be understood that I do not wish to restrict myself to the use of steam, but that the word steam as used in the specification and claims is meant to include and to cover the use of any other appropriate fluid under pressure, and my claims are to be construed accordingly.

What I claim as my invention and desire to secure by Letters Patent, is:

1. In a flue cleaner, the combination of a pipe, a smaller pipe extending through said first-named pipe, means for feeding fluid under pressure to the rear end portion of said first-named pipe about said second-named pipe, means for closing the rear end of said first-named pipe about said smaller 125 130

- pipe in rear of the point of admission of said fluid under pressure, a flexible connector extending loosely through said smaller pipe and closed off thereby from the fluid under pressure in said first-named pipe except at the open front end portion of said smaller pipe, and a cleaning device connected to the forward end portion of said flexible connector and adapted to be projected along a flue by the force of the fluid under pressure delivered through said first-named pipe to the flue in rear of the cleaning device. 50
2. In a flue cleaner, the combination of a pipe, a tapering discharge nozzle of greater diameter than that of said pipe secured on the forward end of said pipe, a smaller pipe extending through said first-named pipe and into said nozzle, closure means for closing the rear end of said first-named pipe about said smaller pipe, means for feeding fluid under pressure to the rear end portion of said first-named pipe in front of said closure means, such fluid under pressure being free to move forward within said first-named pipe about said smaller pipe, a flexible connector extending loosely through said smaller pipe and closed off thereby from the fluid under pressure in said first-named pipe except at the open front end of said smaller pipe, said flexible connector being adapted to move freely through said smaller pipe, and a cleaning device connected to the forward end portion of said flexible connector and adapted to be projected along a flue by the force of fluid under pressure delivered through said first-named pipe to the flue in rear of said cleaning device. 55
3. In a flue cleaner, the combination of a pipe, a smaller pipe extending through said first-named pipe, a housing communicating with the rear end portion of said second-named pipe, said housing being completely closed except for its communication with said pipe, means for feeding fluid under pressure to the rear end portion of said first-named pipe about said second-named pipe, means for closing the rear end of said 60
- first-named pipe about said second-named pipe in rear of the point of admission of said fluid under pressure, a flexible connector extending loosely through said second pipe and closed off thereby from the fluid under pressure in said first-named pipe except at the open forward end portion of said smaller pipe, means located within said housing for drawing said flexible connector backward through said second-named pipe, and a cleaning device connected to the forward end portion of said flexible connector and adapted to be projected along a flue by the force of the fluid under pressure delivered through said first-named pipe to the flue in rear of said cleaning device. 65
4. In a flue cleaner, the combination of a cleaning device adapted to be projected along a flue by the force of fluid delivered to the flue in rear of said cleaning device, a flexible connector connected to said cleaning device and adapted to be projected into said flue with said cleaning device, a head operatively connected with said cleaning device, means for delivering fluid to a flue to be cleaned, and a conical spring carried by said fluid-delivery means against which said head is adapted to be brought for stopping the rearward movement of the flexible connector upon its withdrawal from the fluid. 70
5. In a flue-cleaner, the combination of a pipe, an engaging member fixed on the forward end of said pipe, a conical spring secured in said member, a rod having a head adapted to be brought into engagement with the forward end of said spring, a cleaning device revolvably mounted on the forward end of said rod, said cleaning device being adapted to be projected along a flue by the force of fluid delivered to said pipe in rear of the cleaning device, a flexible connector connected to said rod and adapted to be projected into said flue with said cleaning device, and means for retracting said flexible connector. 75
